UNITED STATES PATENT OFFICE.

CHARLES B. VAN VORST AND NINA E. FULKERSON, OF LOS ANGELES, CALIFORNIA.

MATTRESS AND CUSHION.

1,253,750.

Specification of Letters Patent. Patented Jan. 15, 1918.

Application filed November 24, 1915. Serial No. 63,838.

To all whom it may concern:

Be it known that we, CHARLES B. VAN VORST and NINA E. FULKERSON, both citizens of the United States, residing at Los Angeles, in the county of Los Angeles and State of California, have jointly invented new and useful Improvements in Mattresses and Cushions, of which the following is a specification.

10 This invention relates to mattresses and cushions, and it has for its object to provide improvements in devices or structures of this kind with respect to maintenance of proper form and condition whereby the 15 length of life and comfort and satisfaction in use of such mattresses or cushions will be increased, due to increase of strength and resistance to wear and strain incident to service, and prevention of slipping or dis- 20 arrangement of the filler or body or stuffing portion or portions. Numerous attempts have been made to provide mattress and cushion constructions which will produce the result above stated, but all of them are 25 open to numerous objections concerning expensiveness, want of positiveness and effectiveness in use or service, and general inefficiency. The present invention has for its object to provide improved mattress or cushion constructions embodying or containing the above general required or desired features, which will be relatively simple and inexpensive in construction or formation, positive in operation and durable in use and 35 service, which will be slight in appearance, and which will be generally superior in efficiency and serviceability, rendering the mattress or cushion comfortable to the user and causing the same to be maintained in 40 proper usable shape or condition under long continued service.

With the above and other objects in view, the invention consists in the novel and useful provision, formation, construction, combination, association and relative arrangement of parts, members and features, all as hereinafter described, shown in the drawing, and finally pointed out in claims.

In the drawing:

50 Figure 1 is an isometric view of an improved mattress formed, constructed and organized in accordance with the invention, the upper covering of the same being shown as ripped loose and turned back at one corner of the same, and parts being broken

away and sectioned for clearness of illustration;

Fig. 2 is a vertical sectional view through one end of the mattress shown in Fig. 1;

Fig. 3 is an inner face view of one of the 60 coverings of a modified form of mattress, organized, formed and constructed in accordance with the invention; and,

Fig. 4 is a transverse sectional view through the covering shown in Fig. 3, showing the fullness provided in the covering proper.

Corresponding parts in all the figures are designated by the same reference characters.

Referring with particularity to the drawing, the improved mattress is shown in Figs. 1 and 2 as comprising top and bottom covers A and B respectively, between which extend side or edge covers C, all of which are secured together to form an inclosing case 75 for the filler or body or stuffing D, which as shown in the drawing may consist of layers d of felt or other suitable material. All of the covers are preferably formed of suitable textile material, although other flexible material may be employed. The side or edge covers C are of any preferred form and pattern, and the top and bottom covers may be of any particular shape or pattern desired, in accordance with the general design of the 80 mattress or cushion. Each of the top and bottom covers A and B is provided with a plurality of spaced tufts E, usually arranged at evenly spaced intervals, such tufts being connected together by cords or stitching in the usual manner, the latter being passed through the body or filler D, in order to draw each of the covers A and B down intimately upon or against or into the body 85 D, in a line extending between the tufts E, 90 so as to produce a subdivided mattress or cushion formation, after the pattern predetermined by the relative arrangement and spacing of the tufts E. To prevent shifting or slipping of the body or filler D within 95 the casing consisting of the covers A, B and C, the material of such covers A and B is drawn by the tufts as at 5, forming plaits extending between the tufts, such plaits, when the covers are in place, constraining 100 the mattress body from slipping, and producing a tight, permanent, satisfactory disposition and arrangement of the body or filler within the case. Alternating with the 105 transverse rows of tufts, and preferably 110

midway between the same, we provide strips 6 of tape or other inelastic material, cut to the exact width of the finished mattress or cushion, and stitched to the respective covers A and B thereof near the ends of such strips and slightly inward of the cover edges, as at 7, and at both ends of said strips, and stitched to the cover midway between the stitched ends, as at 8, thus providing for fullness of mattress covering as well as guarding against the lateral spreading of the same due to use or storage. Other strips 9 may extend longitudinally of the mattress, from end to end thereof, preferably midway between the longitudinal rows of tufts, such longitudinal strips 9 being preferably cut to the exact length of the finished mattress and being stitched to the respective covers A and B near the ends of such strips and near the ends of the respective cover, as at 10, and being stitched to the cover midway between the ends of such strips 9 and the ends of the covers, as at 11, such stitching providing fullness of mattress cover from end to end, and preventing the stretching or distortion longitudinally of the mattress. In the finished mattress, the extreme ends of the strips 6 and 9 are sewed onto the edge covers C together with the top and bottom covers A and B. The mattress cover is preferably only stitched at the places described so that the covers are not bound to and united with the strips at too many points, but are free, to the extent allowed by the fullness provided in such covers, to be properly adjusted and to properly conform to the surface requirements of the mattress, and permit the proper tufting of the same.

40 In the modified form of mattress cover illustrated in Figs. 3 and 4, only transverse strips 6 are employed and these strips are stitched to the respective cover A or B, only the inside of the cover A being shown in Fig. 3, such stitching being near the ends of the strips 6, as at 7, and at a point midway between the stitches 7, as at 8, and when the covers A and B are united to the edge covers C in assembling the mattress, 45 the extreme edges of the strips C, which are of a length corresponding to the exact width of the finished mattress, are stitched down to the edge covers with the edges of their respective top and bottom covers. In Fig. 4, which is a transverse sectional view through a mattress cover such as is shown in Fig. 3, the fullness of the cover A is illustrated, a strip 7 being shown as stretched tight as it would tend to do under spreading strains imposed on the mattress, and it will be clear from this figure how the stitching 8 midway between the stitching 7 near the ends of the strip provides for fullness of mattress cover at both sides of the stitching 50 8 as at a and b.

The stitching of the reinforcing strips between their ends facilitates filling of the mattress by holding the strips close to the cover, and it will be understood that while such stitching is shown as midway between the ends of the reinforcing strips, the strips may be stitched at other suitable points, providing that long portions of the strips are free from the covers so that the covers and strips may be independently stretched. 70

The method of use and advantages of the invention will be understood from the foregoing description, taken in connection with the accompanying drawing and the following statement.

The strips 7 having their ends stitched fast to the edges of the respective top and bottom covers and the edge covers C, take care of all lateral spreading strains as the strips are of inelastic material and of sufficient width to provide the required strength, and the covers may be plaited and drawn into the filler by the tufts which produce depressions in the covers, the fullness of the covers, as illustrated at a and b permitting plaiting and inward distortion of covers at the tufts to provide the required or desired mattress or cushion surface and permit the cords and stitches which pass through the covers and the filler to be drawn tightly so as to prevent slippage or displacement of filler and conserve the proper arrangement and distribution of such filler, thus insuring the best and most serviceable condition of mattress or cushion with respect to both comfort of user and appearance. 90

It is apparent that when the longitudinally extending strips 9 are used in addition to the transverse strips 6, both lateral and longitudinal expansion or stretching of the mattress will be prevented, and as whatever strips may be employed are free from the cover for relatively great portions of their length, being in fact, only secured to the covers at the edges of such covers and at the point intermediate such edges, the cover is free to a certain extent to yield to the pull incident to strains imposed upon the mattress and to conform to the tufting requirements, independently of the strips whose function is to prevent spreading. 105

Having thus disclosed our invention, we claim and desire to secure by Letters Patent:

1. A mattress or the like having a cover, parallel lateral reinforcing strips extending from edge to edge of said cover, and rows of tufts alternating with said reinforcing strips and arranged between the same, said reinforcing strips being secured at their ends to the edges of the cover and being taut and shorter than the width of the cover and free from said cover for relatively great portions of their lengths. 110

2. A mattress or the like having a cover, 115

parallel lateral reinforcements extending from edge to edge of said cover, and tufts alternating with said reinforcements and between the same; said reinforcements being secured at their ends to the edges of the cover and being secured to the cover at the median line thereof; said reinforcements being taut and shorter than the width of the cover.

In testimony whereof, we have signed our 10 names to this specification in the presence of two subscribing witnesses.

CHARLES B. VAN VORST.
NINA E. FULKERSON.
